F. F. BRENDLE.
DIRECTION INDICATOR FOR VEHICLES.
APPLICATION FILED NOV. 26, 1919.

Patented June 15, 1920.

UNITED STATES PATENT OFFICE.

FRANK F. BRENDLE, OF SALINA, KANSAS, ASSIGNOR OF ONE-THIRD TO ROY C. CARRUTHERS AND ONE-THIRD TO MYRTLE CARRUTHERS, BOTH OF SALINA, KANSAS.

DIRECTION-INDICATOR FOR VEHICLES.

1,343,761.

Specification of Letters Patent. Patented June 15, 1920.

Application filed November 26, 1919. Serial No. 340,951.

To all whom it may concern:

Be it known that I, FRANK F. BRENDLE, a citizen of the United States, residing at Salina, in the county of Saline and State of 5 Kansas, have invented certain new and useful Improvements in Direction-Indicators for Vehicles, of which the following is a specification.

This invention relates to direction indicators for vehicles and it is the dominant object of the invention to provide a pneumatically operated signal capable of being attached to and operated from the driver's seat of a vehicle, whereby change 10 in direction of the course of the vehicle may be clearly signaled to other vehicles and pedestrians thereby allowing ample time to avoid the vehicle displaying the signal and preventing collisions, accidents 15 or the choking of traffic.

Another and equally important object of the invention is to provide means for automatically returning the signal means to inoperative position subsequent to a signaling 25 operation, thereby rendering the same ready for further use.

Yet another object of the invention is to provide an audible signal operable upon movement of the main or visual signal 30 means to its inoperative position.

Other independent objects are to provide features of construction of portions of the device which tend toward the attainment of the above aims irrespective of the relation in which they are used.

Other objects will be in part obvious and in part pointed out hereinafter.

The invention accordingly consists in the features of construction, combination of 40 elements and arrangement of parts which will be exemplified in the construction hereinafter set forth and the scope of the application of which will be indicated in the following claims.

45 In the accompanying drawings, wherein is shown one of various possible embodiments of my invention.

Figure 1 is a vertical longitudinal section through the improved signal; and

50 Fig. 2 is a transverse section therethrough.

Referring now more specifically to the drawings and in connection with which like reference characters will designate corresponding parts in the several views, 1 represents the tubular cylinder of the device,

the same being supported upon a suitable fixed support or other object by means of brackets 2. The rear end of the cylinder 1 is screw threaded and engaged by a T fitting 3, the opposite end of which is partially closed by a stuffing gland 4, while the remaining extension is engaged with a screw threaded nipple 5, the said nipple in turn, being connected to a hose or other 65 form of conduit 6, the said conduit having engagement with a multi-way valve 7. It is of course to be understood, that the conduit 8 extending from the multi-way valve is in communication with a suitable source 70 of air supply arranged at a point convenient upon the vehicle and capable of being replenished from time to time.

Slidably arranged within the tubular cylinder 1 is a piston 9 provided with a suitable rod having a screw threaded intermediate portion 10 while portions thereof are squared as at 11 and rounded as at 12, the rounded extremity of the rod being provided with a longitudinally extending way 80 13, the said way opening onto the squared extremity 11 and onto the outer extremity of the rounded portion 12. In this connection, it is to be noted that a whistle 14 is arranged on the outer end of the rounded 85 extremity 12 and communicates with the said way 13 whereby it may be operated at times. Mounted in the cylinder 1 and having bearing upon the stuffing gland 4 and the adjacent side of the piston 9 is a 90 contractile coiled spring 15, which spring, obviously, serves as means for normally maintaining the said piston 9 in a position adjacent the rear end of the cylinder 1, thus maintaining the signaling means, 95 hereinafter more fully described, in inoperative position.

Curved spring arms 16 are secured to portions of the rounded extremity of the piston rod as at 17 and have the free ends 100 thereof extending to points in proximity of the outer end of the said rounded extremity. A signal cloth 18 is secured to the oppositely disposed spring arms 16 and to the rounded extremity 12 of the piston 105 rod as at 19. Upon the cloth 18, matter indicating the movements or the directions in which a vehicle is to travel may be arranged, such as for instance words "Stop" "Right" or "Left."

110 A circular piece 20 is carried upon the end of the rounded extremity 12 of the pis-

ton rod and is adapted to be engaged over the open outer end of the tubular cylinder 1 when the piston assumes a position adjacent the rear end of the said cylinder, thus 5 effectively closing the same.

When employing my improved pneumatic operated signal, a plurality of the same are used, having different words arranged upon the respective signal cloths thereof, it of 10 course being understood, that conduits 6 are extended into engagement with each of the tubular cylinders of the various signals and that these conduits in turn are connected to the ports of the multi-way valve 7 whereby 15 the same may be selectively operated.

In operation, air is admitted to the tubular cylinder 1 by way of the multi-way valve 7 and the conduit 6 thereby forcing the piston 9 forwardly and allowing the 20 spring arms 16 to be expanded, thus permitting the displaying of the signal cloth 18 in an efficient manner. Rotation of the piston rod and hence, the signal cloth is avoided due to the squared extremity 11 of 25 the piston rod, which, as will be noted, passes through the stuffing gland 4 arranged upon the rear end of the cylinder 1. Due to the fact that the way 13 extending longitudinally of the rounded extremity 12 of the piston 30 rod is of less size than the bore of the cylinder 1, air will be slowly exhausted therethrough and as a consequence, will operate the whistle 14 carried thereby; attracting attention to the signal and allowing ample 35 time for following vehicles and pedestrians to avoid the vehicle displaying the signal. To return the signal cloth of the indicator to its inoperative or non-signaling position, the multi-way valve 7 is closed whereupon 40 the contractile spring 15 moving the piston rod inwardly and collapsing the signal cloth 18, causes gradual discharge of the air in the cylinder through the port of the whistle 14. When the signal has been fully re- 45 tracted, the end piece 20 carried upon the end of the rounded portion 12 will be engaged over the open end of the cylinder 1, thus effectively closing the same.

Manifestly, the construction shown is capable of considerable modification and such modification as is within the scope of my 50

claims, I consider within the spirit of my invention.

I claim: —

1. A vehicle signal, including a cylinder 55 having an inlet port, a piston working in said cylinder, a rod extending from the piston having a way formed therein and communicating with the cylinder, a whistle arranged in said way, and a collapsible signal carried on said rod.

2. A vehicle signal, including a cylinder having an inlet port, a piston working in said cylinder carrying a rod, said rod having a way extending therethrough and communicating with the cylinder, a whistle arranged in said way, curved spring arms secured to the rod, a flexible signal engaged with said spring arms and said rod, an end piece carried by the rod engageable over the 70 end of said cylinder upon retraction of the piston therein, and spring means in the cylinder for normally maintaining said piston in retracted position.

3. A vehicle signal including a cylinder 75 having an inlet port, a piston reciprocably mounted in said cylinder, a rod carried by the piston provided with a longitudinal passage to permit gradual discharge of air from the interior of the cylinder, spring 80 means normally tending to withdraw the piston and rod, and a flexible signal carried by the terminal of the rod adapted to be withdrawn and concealed within the cylinder during retraction of the piston by the 85 spring means.

4. A vehicle signal including a cylinder having an inlet port, a piston reciprocably mounted in said cylinder, a rod carried by the piston having a longitudinal passage 90 communicating with and adapted to permit discharge of the air from the interior of the cylinder, spring means normally tending to withdraw the piston, a signal carried by the terminal of the rod adapted to be withdrawn 95 into the terminal of the cylinder, and an audible signal operable by the air discharged through said passage.

In testimony whereof I affix my signature hereto.

FRANK F. BRENDLE.
